United States Patent Office.

P. M. PAPIN, OF ST. LOUIS, MISSOURI,

Letters Patent No. 77,401, dated April 28, 1868.

IMPROVED QUARTZ-STAMP MILL.

The Schedule referred to in these Letters Patent and making part of the same.

TO ALL WHOM IT MAY CONCERN:

Be it known that I, P. M. PAPIN, of St. Louis, in the county of St. Louis, and State of Missouri, have made certain new and useful Improvements in Apparatus for Stamping and Mining Purposes; and I do hereby declare that the following is a full and clear description thereof, reference being had to the accompanying drawings, and to the letters of reference marked thereon:

This apparatus is intended for the general mining purposes of small operators, and relates to several devices, having for their object the same ultimate result, viz., the extraction from mines and reduction of ores. In brief, the apparatus consists of a series of vertical stamps, surrounding and operated by a horizontal drum, the top face of which has a serrated railing, forming a series of inclined planes, which elevate and then let drop the stamps as the drum revolves, the said stamps being elevated by means of pins or sheaves attached thereto, sliding or rolling up on the aforesaid revolving serrated railing.

The particular features of the invention relate, firstly, to a device for producing an adjustable stroke of the stamp; secondly, to the combination of a revolving or drill-stamp with a fixed or simply vertical stroke-stamp, arranged in the same stamp-box; thirdly, to the construction and arrangement of the drill-stamp, which may be operated either automatically or by hand; fourthly, to the construction and arrangement of the stamping-box in two compartments, the floor of one of which shall be higher than that of the other; fifthly, to a friction-brake, for regulating the force of the blow given by the stamp; and sixthly, to the peculiar construction of the driving-drum, which adapts it to the propulsion of the mining-pumps or lifts.

To enable those skilled in the art to make and use my improved mining-apparatus, I will proceed to describe its construction and operation.

Figure 1 of the drawings is a central sectional elevation.

Figure 2 is a general plan.

Figure 3 is a side elevation of the friction-brake for stamp.

Figure 4 is a top view of stamp-shoe, showing the radial corrugations acted upon by the spring-pawl to turn the stamp.

Figure 5 is an enlarged sectional elevation of stamp-box, taken on the line *x y* of fig. 2.

The actuating-drum *A* is erected upon a vertical driving-shaft, *A'*. On top of this drum is a series of inclined railings, *a*, surrounding the drum near its periphery, and forming a kind of serrated rim, which, as it revolves, passes successively under each of the pins or sheaves *b*, that project from the inner sides of the stamping-rods *B* or *B'*, and in this manner the stamps are raised, much in the same manner that they are in the Murray machine, patented in 1859.

The drum *A* may operate any desired number of stamps *B* *B'*, the said stamps being arranged around the periphery of the drum, and just close enough to it to be operated by the railing or cams *a*. The pins or sheaves *b*, which are attached to the stamping-rods for the purpose of elevating them, are rendered adjustable as to height by means of the set-screws, *b'*, which are made to enter grooves cut in the stamp-rods at different heights, as shown in fig. 1. In this manner the said sheaves *b* may be adjusted to any height, and the rod still permitted to revolve, as hereinafter explained. The object of this adjustable arrangement of the sheave is to cause the stamp to strike a blow more or less severe, as may be required.

It is found that in the ordinary stamping-mills, a portion of the mineral remains untouched by the stamps, owing to its being forced up at the sides of the stamps. To overcome this difficulty, I use two stamps, *B* and *B'*, in battery in the same stamping-box, the stamp *B* being a round one, and made to revolve like a drill, while the stamp *B'* is made square, and operated in a fixed position. The ore is to be first placed under the revolving stamp *B*, which, by its combined revolving and vertical stroke, will have access to every portion of the unbroken ore, and thoroughly crack and break up the large pieces, which will then be passed under the square stamp, that will then be able to thoroughly pulverize the partially-broken ore.

The shoe, *B*², of the revolving stamp, has its top end provided with radial serrations, as is clearly shown in

figs. 1 and 4. The spring-pawl *d*, attached to the framework *D*, will engage one of these serrations at each upward stroke of the stamp, and turn it around a little like a stone-drill, the striking or lower face of the stamp-shoe *B*² being arranged with corrugations or cross or star-shaped raised ridges; then, owing to said turning of the stamp, the said ridges of said striking-face will be permitted to strike new material at each stroke, thereby thoroughly breaking up all of the large pieces.

The drill-stamp may be turned around by means of a bar or lever, without the aid of the pawl *d*.

The floor of the stamping-box *E* should be made, say, two or three inches (more or less) higher than the floor of the box *E'*, and the two boxes separated by the partition *e*, as shown in fig. 5. The drill-stamp will operate in the higher box, *E*, from which it will be quite easy to pass the partially-broken ore down into the finishing-box, *E'*, by raising the dividing-partition *e*, and from the last box *E'*, the pulverized ore will be discharged through the gate, *e'*, into the central trough *F*, where it will be further reduced by the arastras *G*, which are to be drawn around over the mass of broken ore by the chains *g*, attached to the arms *A*², projecting from the driving-shaft. The trough *F* may be used also for amalgamating purposes.

In order to regulate the force of the blow given by the stamps, I apply a friction-brake, *H*, which consists of a small roller, arranged to press against the side of the stamp-rod, and a lever, arranged to press the said roller up against the said rod more or less severely, as may be desired. This may be accomplished temporarily by pressing on the lever with the hand of the operator, or, more permanently, by the application of a weight applied to the lever, which weight may be moved out toward the end of the lever, as may be desired.

Attached to the bottom side of the drum *A* is a series of vertical arms, *a*, around which a belt, *I*, may be placed, so as to actuate a counter-wheel, *I'*, the latter wheel being used to drive the pumping or lifting-machinery of the mine.

To prevent the roller *b* from moving off the track *a* when the drill-stamp *B* is turned, I guide said roller by the projection *b*³ on the sleeve *b*² running in the slot formed by the guide-plate *b*⁴ and the frame-piece *D*⁴.

Having described my invention, what I claim, is—

1. The stamp *B*, its serrated shoe *B*², and the spring-pawl *d*, when arranged and operated as herein described and set forth.
2. The stamping-boxes *E* *E'*, when constructed with the floor of one higher than that of the other, and arranged as herein described and shown.
3. The friction-brake *H*, when applied to the rod *B* or *B*¹, as and for the purpose set forth.

P. M. PAPIN.
